UNITED STATES PATENT OFFICE.

CLIFFORD NORTON, OF ORANGE, NEVILLE S. DICKINSON, OF GLEN RIDGE, AND RUMSEY W. SCOTT, OF MONTCLAIR, NEW JERSEY, ASSIGNEES TO ELEVATOR SUPPLIES COMPANY, INC., OF HOBOKEN, NEW JERSEY, A CORPORATION OF NEW JERSEY.

GATE-OPERATING MECHANISM FOR ELEVATORS.

Application filed April 30, 1921. Serial No. 465,906.

To all whom it may concern:

Be it known that we, CLIFFORD NORTON, NEVILLE S. DICKINSON, and RUMSEY W. SCOTT, citizens of the United States, residing, respectively, at Orange, New Jersey, Glen Ridge, New Jersey, and Montclair, New Jersey, have invented certain new and useful Improvements in Gate-Operating Mechanism for Elevators, of which the following is a clear, full, and exact description.

Our invention relates to gate operating mechanism, particularly useful in operating the gates of elevators. Our object is to improve upon and simplify the constructions heretofore known. It is adaptable for use in any type of elevator and therefore the particular means for operating the elevator whether it be of the manually controlled or the push-button type is immaterial. For the purpose of illustration, we therefore have omitted the particular elevator operating or controlling mechanism which it is believed would not add to the clearness of disclosure of the present invention but would only serve unnecessarily to complicate the drawings. The particular construction of gates to be operated is also immaterial. In the present instance, merely as illustrative of one embodiment of the invention, we have shown in the drawings gates which are unitary or in one piece as to each hatchway opening. Such particular type of gates obviously is unnecessary to the embodiment of our invention.

In the drawings, Fig. 1 represents more or less diagrammatically a hatchway in which travels a car (not shown) attached to the hoisting cable 2 passing around a hoisting drum 3. Three floors are shown with an opening in each floor closed, respectively, by the gates 102, 103 and 104. The gate 103 is shown in its open position;

Fig. 2 is a partial sectional view of the gate 104 and its associated mechanisms, representing the gate in its closed position;

Fig. 3 is a similar view of the opened gate 103;

Fig. 4 is a diagrammatic view of the electrical connections;

Fig. 5 is a diagrammatic view of the "knock out" cams and associated switches

shown in Fig. 4 but represented in substantially the position they take when a gate is fully opened;

Fig. 6 is a detail;

Fig. 7 is a simplified diagram of a portion of the electric circuits in the position when the gate is at rest in its fully opened position;

Fig. 8 is another electrical diagram; and

Fig. 9 is a detail of the clutch and gate-operating drum of one of the gates.

In the above preferred embodiment of our invention, the gates 102, 103 and 104 close the openings at their respective landings. These gates may, if desired, be of the "offset" type which, when they start to open, are swung into the hatchway so as to clear the sill and gate of the floor above in their upward travel. Referring to Fig. 2, it will be seen that the gate 104 rests on the sill 104a. It may be locked in this position by the latch 143 connected to a lever 144 which may be struck by a cam (not shown) on the car. At each gate is a drum 109 (see Fig. 9). Around this drum are wound two cables 110 and 111, each of which is connected to the gate, as shown for example at 110' and 111' in Fig. 1. 112 is another cable wound around the drum and attached to the counter-weight 113. 115 (Figs. 2 and 3) is a slide operating in a guideway and connected to the gate by links 117 and 118. Obviously when the drum 109 is rotated, the gate will first be swung, like one side of a parallel ruler, inward from its position indicated in Fig. 2 to the offset position indicated in Fig. 3, where block 140 contacts with block 141 carried by the slide, and then will travel upward in a position to clear the sill and gate of the floor above. This construction, of course, is merely illustrative of one type of gate which may be employed.

The drum 109 is fixed to its shaft. Loose on this shaft is a friction clutch disk 120 having gear teeth engaging with a driving chain 107. The clutch portion 121 is rotatable with but slidable longitudinally on the drum shaft. When this is thrown to the left in Fig. 9, it clutches the drum shaft to the friction disk 120 and so transmits power from the chain to the drum. Obviously the friction disk is adapted to slip if the door

is overdriven. 122 is an operating device for the clutch, which may be a magnet with suitable lever connections.

The driving chain 107 is endless and passes over a pulley 106 in the pent house and a suitably weighted pulley 107^a at the bottom of the hatchway. Power is supplied to the driving pulley 106 by a gate-operating motor 105 which, with its driving chain 107, is

10 common to all of the gates and their clutches.

For controlling the travel of the gates we prefer to provide a construction which shall be operated by the movement of the gates themselves as distinguished from being operated directly by the motor which operates the gates. We find this is preferable because, for one reason, it insures that the gates shall be fully opened and fully closed before the motor ceases to act. In the present embodiment of our invention we have provided for this purpose an endless cable 125 passing over a pulley 124 which is connected by a suitable belt 130 to rotate a shaft 132 on which are located the "knock outs" or movement-limiting cams 133 to 139 inclusive (see Figs. 4 and 5).

The cable 125 has fastened to it at each floor a weighted ball 128. Each gate has projecting from it (see Fig. 2) a hooked portion 127 loosely embracing the cable 125. When all the gates are shut, each one of the fingers 127 has resting on it and supported by it one of the weighted balls 128. As a gate, such for example as 103, travels up, its hook 127 carries upward the ball 128 and therefore the cable 125, so rotating the pulley 124 and consequently the "knock out" shaft 132. As the gate descends, the combined weights of the balls 128 cause the cable 125 to move in the opposite direction and follow the gate downward to its closed position, being sufficient in the aggregate to overcome the friction of the shafts rotated by the cable 125.

45 A selector, generically indicated by 145 and hereafter to be more specifically described, is operated correspondingly to the movement of the car, preferably by being connected as indicated in Fig. 1 to the winding drum or other moving portion of the elevator. This selector, shown diagrammatically at the right of Fig. 7, may comprise stationary blocks and a moving brush 146, which travels back and forth over them as the car moves. The hoisting motor for rotating the hoisting drum 3, to which the car is attached, is not specifically shown in this figure.

30 Referring to Fig. 4, the gate-operating motor 105 is shown at the right with a spring-pressed brake 148 released when magnet 149 is energized. Three gate clutches 122, 220 and 223 are shown, one for each gate. At the upper left-hand corner of the diagram are represented buttons, in the pres-

ent case electric switches, which can open, close and stop the doors. Those represented by 205, 181 and 195 are located in the car and serve, respectively, to stop, open and close a gate. 210, 213 and 216 indicate the similar buttons located outside the hatchway on the first floor; the second and third floors are provided with similar outside buttons.

75 Preferably, the operation of the gates is accomplished by electrical mechanism and such has been shown. We also prefer to have only one main magnet for controlling the opening movement and another one for controlling the closing movement, these being 80 common to all the gates. Such magnets have been shown in Fig. 4 by 153 and 154. A selector commutator is shown consisting of a stationary feed strip 147 and stationary contact blocks 230, 231, etc., together with 85 a moving brush 146 for making the proper connections. 156 is a solenoid magnet for making connections hereafter to be described.

90 Fig. 8 represents a diagrammatic view of a portion of the electrical circuits more particularly with relation to the opening movement of the gate. The position shown is that in which the parts are when the car has reached the third floor and the power has been shut off. The moving brush 146 is then 95 on the contact blocks 200, 219 and 164 corresponding to the third floor. A circuit may then be traced from the lead III through the stop switch 205, switch 38, "knock out" switch 161, solenoid magnet 153, 100 switches 162 and 163 to contact block 164 and by brush 146 and out. This will energize solenoid 153 and cause it to move its core upward. This will close the switches 166 and 169 at the top and the switches 190 and 191 at the bottom. When switch 169 closes, it completes a circuit from the lead III to the point 175 to the point 170, switch arm 270 and by way of resistance 171 to the gate motor 105. The motor therefore begins to rotate and drives the chain 107 rotating also the friction gears 120. The gate, however, does not move until the clutch is thrown in.

110 The clutch is energized by the selector having selected the proper magnet such as the third floor magnet 122. This is energized from the lead III by way of point 192 and switch 191, through magnet 122 to block 200 and out. This clutches the hoisting drum 109 of that gate to the driving chain 107, 115 and the gate begins to rise, carrying with it the cable 125 and starting the shaft 132 and the "knock outs" to rotating in the direction of the arrow indicated close to "knock out" 120 134 in Fig. 5. As soon as the door starts to rise, the "knock out" 134 releases its switch arm 193 which then closes a by-pass circuit through the clutch magnet 122 and this remains energized until the door again reaches its closed position, the gate thus being 125 130

clutched continuously to the motor until it reaches its fully closed position.

It is desirable to start the gate slowly, particularly as it is often heavy, then to increase its speed and gradually to bring it to rest as it approaches the limit of its movement in either direction. In Fig. 4 we have represented, as actuated by solenoid 150, a switch for varying the speed of the motor. In Fig. 8, however, we have shown a simplified construction for greater clearness and simplicity. In Fig. 8, when switch 169 closes, the resistance 171 is in circuit with the motor 105. After the gate is offset, "knock out" 139 leaves its switch arm 172, which then closes, and energizes solenoid 150 drawing up its core and cutting out the resistance 171. The motor therefore continues to rotate faster and moves the gate more swiftly until it approaches its upward limit of movement when "knock out" 138 strikes lever 172 as indicated at the right of Fig. 5, reopening the circuit of solenoid 150 and reinserting the resistance 171, thus slowing down the gate. As the gate reaches its upward limit of movement, the "knock out" 137 reaches the position indicated in Fig. 5, opens the circuit of magnet 153, and the core of that magnet drops, reopening the motor circuit and stopping the motor. As above described, the clutch 122 still remains energized, keeping the gate still clutched to the motor.

The motor 105 (see Fig. 4) is normally held from rotation by its brake 148. It is desirable that this brake shall be released as soon as, or rather an instant prior to the time, the gate starts to open. This may be controlled in a variety of ways from the elevator. In the present embodiment we have illustrated a switch 38 which is held open so long as the car is not slowed down but which, when the car slows down to stop, automatically closes. We have illustrated at 11^a one embodiment of such a switch, such as a centrifugally operated construction which will close the switch as the car slows down to stop. In Fig. 8 we show another form for accomplishing this result, in which A is the hoisting motor for the car, B a starting resistance and D a moving switch for controlling the car, and a magnet 11 for normally holding open the switch 38, but which allows the switch to close when the car has been slowed down, by cutting off the power. When switch 38 is closed a circuit is completed through the point 196, brake magnet 149 and switch 168. This will immediately draw up the core of solenoid 149 and release the brake. As the "knock out" 136 releases this switch arm 168 immediately as soon as the gate starts to rise, a by-pass circuit must be provided. This may be traced from the magnet 149 to the switch 190 to the point 180, 165, switch 162, 163 and

cut. The circuit through switch 162, 163 is immediately broken, as will be later described, and this would open the brake circuit but a by-pass is provided from the point 165 to switch 166 and out. Thus the brake is normally removed from the motor just prior to the time its circuit is closed and remains off until solenoid 153 is deenergized. As the gate remains clutched to the driving chain 107 until the door again reaches its closed position, the gate is restrained from downward movement in its fully opened position by the brake of the motor.

If the gate were now closed, it would immediately reopen as soon as it again reached its closed position. In order to prevent such undesired movement, we have provided means for breaking the circuit at the switch points 162 and 163. This is provided by the solenoid 156. When the solenoid 153 is energized, switch 169 closes and a circuit may then be traced by the wire 176, to the block 177, through the solenoid 156 and out. This energizes the latter solenoid and raises its core, breaking the circuit between blocks 162 and 163. A maintaining circuit is provided by way of resistance 230, block 178 on the solenoid core, and out through the solenoid 156. It will be observed that this circuit then remains closed, with switch 162, 163 open, preferably until the brush 146 moves off from the block 164. It cannot do so until the car has moved away from the floor. Consequently the gate cannot be automatically opened again after having been reclosed until the car has left the floor.

It may be desirable that the gate be opened manually instead of automatically, and in any case it is desirable that the car operator be able to open the gate. In such case an "open" button 181 is provided in the car. By closing this, the "open" solenoid 153 may be energized and the gate consequently opened, the same operations then taking place as above described. In the car is also a "stop" button 205. Opening this switch deenergizes magnet 153 and the brake magnet 149 stopping the gate and holding it by the motor brake. Reclosing this switch does not start the gate in either direction nor does it remove the brake from the motor. It does not start the motor because the switch 169 is then opened and it does not remove the motor brake because switches 168 and 190 are then opened. In other words, reclosing the "stop" switch 205 does not start the gate again. The gate, however, can be started upward by closing the "open" button 181 in the car or the similar "open" button 215 (see Fig. 4) for example, outside the hatchway on that floor.

The gate may be closed by closing the switch 195 in the car or the similar switch 218, for example, outside the shaft. The

cam 135 has then, of course, released its switch arm 197. Operating the "close" button will consequently close the circuit through the "close" magnet 154. This operation is more clearly illustrated in Fig. 7. In that figure, the parts are represented as in substantially the position they are when the gate is fully opened but omitting some of the circuits shown in the other figures.

10 Depressing the "close" button 195 in the car, or the similar "close" button 218 outside the hatchway at that floor, energizes the "close" solenoid 154 through the switch 197, so- solenoid 154, point 198, "close" button 195 (or 218), block 164 (or 219 for the floor button) of the selector and out. This energizes the solenoid and draws up its core, closing its switches 201, 278 and 190^a. The latter switch energizes the motor brake solenoid 149 and lifts the brake. The maintaining circuit for the solenoid 154 is then closed by way of switch 201 and out to block 164, keeping also the solenoid 149 energized. This switch 201 also forms a by-pass or 25 maintaining circuit for the solenoid 154 after the operator takes his finger off the "close" button. Switch 278 closes the reversing circuit of the gate motor which then rotates in the opposite direction and is 30 varied in speed as above described, driving the gate in the closing direction. This continues until the gate is normally closed when the "knock out" 139 (Figs. 4 and 8) reopens its switch 172, reinserting the resistance 171 35 and slowing down the motor. As the gate lowers, its slide 115 (Figs. 2 and 3) strikes the stop 142 and the gate then offsets back to the closed and locked position. At this instant the "knock out" 135 reopens the 40 switch 197, deenergizing solenoid 154 and stopping the motor. The "knock out" 136 has then closed its switch 168 keeping the brake thereafter lifted until the car starts and opens switch 38.

45 The parts are then in their original position shown in Figs. 1 and 8 except that solenoid 156 is still energized through its maintaining circuit by way of resistance 230 and wire 277, thus keeping open the switch at blocks 162, 163. If it were not for this, as above explained, the gate when closed would immediately rise again and the gate never could be kept shut or would smash the lock 143 or some of the operating parts.

50 The solenoid 156 and its connections is therefore one form of a mechanism for preventing the gate opening mechanism from automatically reopening the gate after it has been closed. In the present embodiment, solenoid 156 remains energized until the car has moved away from the floor, that is, until the brush 146 passes off from the third floor contacts. When this occurs, the maintaining circuit through the solenoid 156 is 55 broken and it drops to the position shown in

Figs. 4 and 8, leaving the parts ready for a new operation, the switch 38 of course opening when the car starts and remaining open until the car again slows down. If it slows down between floors, nothing happens because the selector brush is not on any of the floor contact blocks.

It will be observed that while the door is opening or while it is closing, either the operator in the car or a person on any floor may stop the gate by pressing any one of the stop buttons. The gate thereafter cannot be started in either direction by anyone except an operator in the car or a person on the floor where that gate is. Only the "open" or "close" buttons outside the shaft on that floor, or in the car which is also at that floor, can start the gate but by them it can be restarted in either of the opening or closing directions. The gates themselves control their speed and stopping. They are controlled in part through selector 145 by the elevator and in part through the "knock outs" by the gates themselves. Selector 145 also controls the door clutches and the "open" and "close" buttons but does not complete the circuits until the switch 38 is closed due to the slowing down of the car. The gates are in the present embodiment automatically opened and held open by the motor clutch and the motor brake whenever the gate is stopped in any even partially opened position. The gate clutch of the operated gate remains energized until the gate again reaches its closed position. The selector selects the individual gate clutches and therefore the gates, the sets of "open" and "close" buttons outside the shaft, the time when the "open" and "close" buttons in the cars can operate the gates, and the time when the gates can control themselves.

In order to make the diagram more clear, we have shown the "open" and "close" buttons as independently operable. They, however, may be arranged so that an "open" button cannot be operated when a "close" button has been operated. This may be accomplished in a variety of ways but it is not thought necessary to illustrate this. In Fig. 6, however, we have shown such an arrangement diagrammatically for the "open" and "close" buttons in the car.

The foregoing construction illustrates the preferred type of embodiment of our invention. We, however, realize that our invention may be carried out in a variety of embodiments, and therefore do not limit ourselves in the constructions heretofore illustrated and described.

What we claim is:

1. In combination, a hatchway and three or more gates along the same, a car, gate-operating mechanism common to all the gates, a selector operated correspondingly with the movement of the car and adapted

- to cause each gate to be opened automatically as the car reaches its floor, and means rendering the gate-opening mechanism operative only when the car has slowed down 5 to stop at a floor.
2. In combination, a hatchway and three or more gates along the same, a car, gate-operating mechanism, a selector operated correspondingly with the movement of the 10 car and adapted to cause each gate to be opened automatically as the car reaches its floor, means rendering the gate-opening mechanism operative only when the car has slowed down to stop at a floor, means for 15 closing the gate and means automatically preventing the gate from automatically opening after it has been so closed.
3. In combination, a hatchway and car, three or more gates along the hatchway, 20 electrically operated gate-opening mechanism common to all the gates, means to connect the gates independently thereto controlled by a selector operated correspondingly with the car and arranged to connect 25 in said gates in succession, and mechanism rendering said selector inoperative unless the car stops at a floor.
4. In combination, a hatchway and car, three or more gates along said hatchway, 30 electrically operated gate-opening mechanism common to all the gates, means to connect the gates independently thereto controlled by a selector operated correspondingly with the car and arranged to connect 35 in said gates automatically and in succession, and mechanism rendering said selector inoperative unless the car stops at a floor.
5. In combination, a hatchway and car, 40 three or more gates along the hatchway, electrically operated gate-opening mechanism common to all the gates, means to connect the gates independently thereto, including "open" and "close" buttons in the 45 car, controlled by a selector operated correspondingly with the car and arranged to connect in said gates in succession, and mechanism rendering said buttons inoperative unless the car stops at a floor.
- 50 6. In combination, a hatchway, three or more gates along the same, gate-opening mechanism including a motor common to all the gates and mechanism to connect in the gates independently and in succession, and 55 means operated by the movement of each gate independently and arranged to continue the operation of the motor until the gate is fully open and then stop the same.
7. In combination, a hatchway, three or 60 more gates along the same, gate-opening mechanism including a motor common to all gates and mechanism, including a friction clutch for each gate, to connect in the gates independently and in succession, means 65 operated by the movement of each gate inde-
- pendently and arranged to continue the operation of the motor in spite of any clutch slipping, until the gate is fully open, and then stop the same.
8. In combination, a hatchway and car, a gate, gate-operating mechanism and means including a selector operated correspondingly with the car and arranged to cause the gate to open automatically when the car reaches a floor, gate-closing mechanism, and 70 means automatically preventing the gate-opening mechanism from then automatically re-opening the gate.
9. In combination, a hatchway and car, a gate, electrically operated gate-operating 80 mechanism and means including a selector operated correspondingly with the car arranged to cause the gate to open automatically when the car reaches a floor, manually controlled electrically operated gate closing 85 mechanism, and means automatically preventing the gate-opening mechanism from then automatically re-opening the gate.
10. In combination, a hatchway and car, a gate, electrically operated gate-operating 90 mechanism and means including a selector operated correspondingly with the car arranged to cause the gate to open automatically when the car reaches a floor, manually controlled electrically operated gate closing 95 mechanism, and means automatically preventing the gate-opening mechanism from then automatically re-opening the gate so long as the selector remains in its gate-selected position.
11. In combination, a hatchway, three or 100 more gates along the same, a car, mechanism common to all gates and controlled independently by the movement of any one and arranged to cause that gate to open fully 105 and close fully after such movements have been initiated, and a selector operated correspondingly with the car and arranged to connect said gates successively to said common operating mechanism.
12. In combination, a hatchway, three or more gates along the same, mechanism to open and shut the gates, buttons in the car and at each floor outside the shaft arranged 110 to cause said mechanism to operate as desired, and a selector operated correspondingly with the car and arranged to connect in the car buttons when the car reaches any floor, but only that set of floor buttons corresponding to the car's position.
13. In combination, a hatchway and a gate at each of three or more floors, a car, means, 115 including in part gate motor mechanism common to all the gates and a gate selector operated correspondingly with the car, arranged automatically to open any gate but only the one at which the car stops.
14. In combination, a hatchway and a gate at each of three or more floors, a car, means, 120 including in part a gate selector operated

- correspondingly with the car, arranged automatically to open any gate but only the one at which the car stops and, common to all gates, a source of power and mechanism controlled by each gate independently and arranged to slow down and then stop that gate at the desired limit of travel.
15. In combination, a hatchway and a gate at each of three or more floors, a car, means, including in part a gate selector operated correspondingly with the car, arranged automatically to open any gate but only the one at which the car stops, means to shut the gate, and automatic means rendering the gate opening mechanism inoperative to open the gate automatically when the gate closes.
16. In combination, a hatchway and a gate, a motor for operating the gate, means for varying the motor speed, and mechanism operated by the movement of the gate and arranged to cause the motor to drive the gate more slowly at each end of its travel and to stop the same.
17. In combination, a plurality of gates along a hatchway, a common source of power for moving the same, means arranged to select and connect to said source of power only the gate corresponding to the car's position, and means common to all said gates and operated by the gate selected and controlling the movement thereof.
18. In combination, a plurality of gates along a hatchway, a common source of power for moving the same, means arranged to select and connect to said source of power only the gate corresponding to the car's position, and means to stop and reverse said source of power intermediate of its travel and without disconnecting said gate.
19. A plurality of gates along a hatchway, a common source of power for moving the same, magnetic clutching means arranged to select and connect to said source of power only the gate corresponding to the car's position, and means to stop and reverse said source of power intermediate of its travel and without disconnecting said gate.
20. A plurality of gates along a hatchway and a common source of power for moving the same, means common to all the gates and operable by each independently and arranged to control the movement thereof, and a selector operated correspondingly with the car and arranged to connect in any gate corresponding to the floor where the car stops.
21. In combination, a plurality of gates along a hatchway and means for operating the same independently, manual means for initiating the movement of said gates, means for automatically continuing the movement of the gate after said manual means has been released, and a selector operating correspondingly to the car and arranged to render said manual means operable only on a gate corresponding with the position of the car.
22. In combination, a plurality of gates along a hatchway and means for operating the same independently, manual means within the car for initiating the opening and closing movements of said gates, means for automatically continuing the movement of the gate after said manual means has been released, and a selector operating correspondingly to the car and arranged to render said manual means operable only on a gate corresponding with the position of the car.
23. In combination, a plurality of gates along a hatchway and means for operating the same independently, at each floor manual means each operable at any time to stop the gate at substantially any point in its movement, manually operated means operable then to start the gate in either direction, and mechanism rendering the latter means operable only at the floor where the car then is.
24. A plurality of gates along a hatchway and means for operating the same independently, means for stopping a gate at substantially any point in its movement, and manual means operable to cause the gate operating means then to move the gate in either direction desired.
25. In combination, a plurality of gates along a hatchway, electrical means for operating said gates independently, manually controlled means for starting a gate, an electric switch and means operated thereby for breaking the circuit and stopping the gate at substantially any point in its travel, and means rendering the re-closing of said switch incapable of causing the gate then to start until said manual starting means is operated.
26. In combination, a plurality of gates along a hatchway and means for operating the same independently, manual means within the car and also at each floor and suitable mechanism controlled thereby arranged to open and close any gate but only the one where the car then is, manual means on each floor and suitable mechanism controlled thereby arranged to open and close only that gate when the car is at that floor.
27. In combination, a plurality of gates along a hatchway, means for operating the same independently, a car, manual means in the car and mechanism operable thereby and arranged to stop any gate at substantially any point in its closing movement, and manually controlled means then to move the gate in either direction.
28. In combination, a hatchway and three or more gates along the same, a car, a gate-operating motor common to all gates, an "open" magnet and a "close" magnet common to all the gates and controlling in part their opening and closing movements, means

- operated by the movement of each gate independently and arranged to control the movement of the gates, a selector arranged to connect in said gates in succession correspondingly with the movement of the car, mechanism arranged to automatically cause said selector to be operative only when the car has slowed down to stop at a floor, "open" and "close" buttons in the car and mechanism operated thereby by which the operator in the car may initiate an opening or closing movement of the gates but only of the gate where the car is.
29. In combination, a hatchway and three or more gates along the same, a car, a gate-operating motor common to all gates, an "open" magnet and a "close" magnet common to all the gates and controlling in part their opening and closing movements, means operated by the movement of each gate independently and arranged to control the movement of the gates, a selector arranged to connect in said gates in succession correspondingly with the movement of the car, mechanism arranged to automatically cause said selector to be operated only when the car has slowed down to stop at a floor, "open" and "close" buttons in the car and mechanism operated thereby by which the operator in the car may initiate an opening or closing movement of the gates but only of the gate where the car is, "open" and "close" buttons at each floor for similarly opening and closing only the gate selected by said selector, and gate stopping buttons at each floor and in the car, said "open" and "close" buttons being arranged to start a gate in either direction desired after having been stopped short of its limit of movement.
30. In combination, a shaft and a plurality of gates along the same, a car; and, common to all said gates, a source of power, a magnet and connections arranged to cause any gate to open, and means controlled by the movement of each gate and controlling its opening movement, a selector operated correspondingly with the movement of the car and mechanism controlled thereby arranged automatically to connect the gates in succession to said source of power, means rendering said selector effectively operative only when the car stops at a floor, means for closing the gate, and mechanism preventing the immediate automatic opening of the gate.
31. In combination, a hatchway, three or more gates along the same, a car, gate operating mechanism, and electrical mechanism operating to cause each gate to be opened automatically as the car reaches its floor, and means rendering the gate opening mechanism operative at a floor only after the car has there slowed down.
32. In combination, a car, a gate at each of several floors, gate operating mechanism thrown into operation automatically when and only when the car slows down at a floor and means for controlling said mechanism arranged to prevent said mechanism from being again thrown into operation automatically while the car remains at the floor.
33. In combination, a car, a gate at each of several floors, gate-opening mechanism thrown into operation automatically when the car has been slowed down to stop at a floor, selecting mechanism arranged automatically to limit such operation to the gate where the car then is, a "close" device operable by the operator while the car is at rest at the floor and arranged to cause the operation of mechanism for closing the gate and holding the same closed after said "close" device is released.
34. In combination, a car, a gate at each of several floors, gate-opening mechanism thrown into operation automatically when the car has been slowed down to stop at a floor, selecting mechanism arranged automatically to limit such operation to the gate where the car then is, a "close" device operable by the operator while the car is at rest at the floor and arranged to cause the operation of mechanism for closing the gate and holding the same closed after said "close" device is released, together with an operator's "open" device arranged so that he may then cause the gate-opening mechanism to operate while the car continues at rest at the floor.
35. In combination, a car, a gate at each of several floors, gate-opening mechanism thrown into operation automatically only after the car has been slowed down at a floor, and controlling means arranged to prevent said gate-opening mechanism from being again thrown into operation automatically while the car remains at rest at the floor, together with a device whereby the operator may cause the gate opening mechanism then to operate while the car remains at rest at the floor.

Dated this 11th day of April, 1921.
